SLIPPER SOCK

Florence W. Van Gundy, Fort Dodge, Iowa

Application February 12, 1954, Serial No. 28,999

Term of patent 3½ years

(Cl. D47—7)

Fig. 1

Fig. 2

Fig. 3

To all whom it may concern:

Be it known that I, Florence W. Van Gundy, a citizen of the United States, residing at Fort Dodge, in the county of Webster and State of Iowa, have invented a new, original, and ornamental Design for a Slipper Sock, of which the following is a specification, reference being had to the accompanying drawing, forming a part hereof.

Figure 1 is a perspective view of a slipper sock, showing my new design;

Figure 2 is a side elevational view thereof; and

Figure 3 is a front elevational view.

I claim:

The ornamental design for a slipper sock, as shown.
